UNITED STATES PATENT OFFICE.

ELIHU THOMSON, OF LYNN, MASSACHUSETTS.

SUSPENDING DEVICE FOR OVERHEAD ELECTRIC CONDUCTORS.

SPECIFICATION forming part of Letters Patent No. 435,870, dated September 2, 1890.

Application filed June 20, 1890. Serial No. 356,115. (No model.)

To all whom it may concern:

Be it known that I, ELIHU THOMSON, a citizen of the United States, and a resident of Lynn, in the county of Essex and State of Massachusetts, have invented certain new and useful Improvements in Suspending Devices for Overhead Electric Conductors, of which the following is a specification.

My present invention relates to the line construction of an electric railway in which the conductor is suspended above the roadway by span-wires or other of the well-known means for this purpose; and its objects are to provide a high degree of insulation for the trolley-wire and a supporting insulator-hanger, simple in its construction yet highly effective, which is alike durable and easily replaceable.

With these objects in view my invention consists, in general, of a sub span or sway wire, preferably insulated, which is attached at its ends to the customary cross-wire of an electric-railway, and from which the trolley-wire is suspended, and, secondly, in a special construction of insulator, all as pointed out in the claims hereinafter made.

The invention will be understood by reference to the accompanying drawings, in which—

Figures 1 and 2 are perspective views showing, respectively, means for supporting a single and two trolley-wires above the street-surface. Fig. 3 is a vertical sectional view of the insulator-hanger. Fig. 4 is a plan view of the same; and Figs. 5 and 6 are detailed views, the former showing a modification of the arrangement in Fig. 3.

In Fig. 1, P P' represent conventionally poles or other supports placed on opposite sides of the street, from which is strung a cross or span wire S, transverse to the roadway and at any desired distance above the street-surface. As will be seen, this span-wire extends straight across from one point of attachment to the other, and is preferably unbroken between the points where it leaves the insulators.

In case a single trolley-wire is to be used, as represented in Fig. 1, I make use of a sup-

plemental wire S', forming a loop depending below the span-wire. This wire is clamped to the cross-wire at two points C C at some distance from the center, and carries at its middle portion the insulator-hanger, which in turn supports the trolley-wire. While the loop of this one may be formed of bare wire, I preferably make it of insulated wire—as, for instance, one covered with a close braid and thoroughly water-proof, two or three layers being desirable. This gives practically an insulating span or loop between the points C C, upon which the insulator I is hung.

When two trolley-wires are supported from the same cross-wire, the arrangement is modified, as in Fig. 2, where T T' are the two trolley-lines and I I' are the insulator-hangers carried on the loop-wire S', which is clamped to the main span-wire at the points C C, as before. It will of course be understood that in supporting a long wire this structure is duplicated at successive points along the line.

While the hanger I may be made in a number of ways, I prefer the following special construction, (shown in Figs. 3, 4, 5, and 6,) which is one capable of being attached to the loop-wire S'. In Fig. 3, S' represents a loop-wire with a heavy braid covering B, treated so as to be water-proof. I prefer also to again cover the wire at the point where it is desired to attach the hanger by a lead tube L, which extends for a short distance each side of the hanger. This tube serves the purpose of preventing abrasion of the braid, while no leakage of current can occur, as it extends for a considerable distance on each side of the hanger I, so that the loop-wire S' is at all times dead. The insulation of the wire S' is, however, a secondary insulation, since the main insulation is in the hanger I itself, which is constructed as follows: A metallic clip M is provided having on each side an offset arm D, curved or bent into a hook at its outer end. The transverse wire is passed around this clip just above the bead G and then bent so as to pass through the hooks D D, as shown in Fig. 4. Through the body of M there is a vertical bore for the reception of a hollow

cylinder or thimble of insulating material, having a stem projecting up into the bore in the clip M and a bell-shaped portion N for shedding water. Through this spool passes

5 a metal screw or bolt provided with a head H, slightly wider than the bore in the clip, and a screw-threaded portion V. The head H is embedded in a cap of insulating material, which keeps it out of contact with the metal clip. 10 In this way not only is the head of the bolt protected from leakage, but it is also impossible for it to be pulled down through the clip, thus detaching the trolley-wire from the span-wire.

15 Secured to the insulator is the part K, acting as a nut for the screw-thread B, to which is attached by a bolt or rivet the ear E, suspending the trolley-wire. Fig. 6 shows these parts more in detail, wherein T is the trolley-wire secured to the lower parts of the ear E, which is pivoted between the cheeks projecting from the nut K, and thereby is permitted 20 a certain amount of swinging motion. A rubber washer is inserted between the insulating-cap around the head H and the insulator-stem, so that in securing these parts together the rubber washer (marked W) is compressed, making a tight joint and keeping out 25 all moisture. In some cases a metallic cover (shown in dotted lines) is placed over the cap and secured by screws at its lower edge, which pass under a flange upon the upper end of the clip M. The insulating material may be 30 porcelain or hard rubber, or of various compositions which are strong, resist compression, and are water-proof.

Fig. 5 shows a modification, where M is, as before, a perforated metal clip which receives the insulator and bolt H. The head of the 40 bolt is sunk in a sort of cup R, the sides of which project upward and retain in position a body of plastic material Q—such as soft pitch—above the head of the bolt, thereby making it practically water-proof.

45 In order to make the joint between the portions of the insulating material tight and at the same time elastic, as respects the metal clip M, I prefer to bevel the outside edges of the piece V' and clip M and to insert rubber 50 rings W W', which are a little too large for the space, and therefore are compressed when the parts are put together. I thus secure elasticity and guard against the entrance of moisture, which might form a leak, by connecting the inner bolt H with the clip M.

It will be understood that the insulator-hanger described may be used with the ordinary span-wire, such as S, omitting the depending loop S'; but in such case the total 60 amount of insulation is not so great. In the same manner the wire S' might have attached to it other insulating devices than the hanger described; but I find that the two co-operate in the best way to secure a thorough insulation and to make a complete structure.

It is a matter of very little difficulty, as will be seen, to adjust the position of the insulator-hanger or to put a new one in place. Furthermore, as the trolley-wire expands and contracts, the strains in one direction or the other will be compensated for by the swinging action of the loop-wire, which allows comparative freedom of movement, as does also the pivotal joint between the ear E and the clamp K. Hence the structure is not liable to get 75 into bad condition due to slight displacements. Furthermore, the insulation of the line-conductor T is very great, for the current to leave such line must penetrate the insulation around the bolt H or cross the depending edges of the water-shed N to reach the metal M; and even if the circuit is completed thus far there is still a long distance to be traversed over the exterior insulation, due to the braid B, before the main span-wire S is reached. Hence the span-wire may be grounded or not. It may, in fact, be the means of support for guard-wires without the slightest electrical connection with the trolley-line.

What I claim as new, and desire to secure by Letters Patent, is—

1. The combination, with the span-wire of an electric-railway-line structure and a supplemental wire connected thereto and forming a depending loop, of the line-conductor suspended from the loop, as described.

2. The combination, with the span-wire of an electric-railway structure and a supplemental insulated wire attached thereto and forming a depending loop, of an insulator-hanger attached to the supplemental wire and sustaining the line-conductor, as described.

3. The combination, in an electric railway, with a transverse insulated wire, of a protecting-casing, as L, an insulator-hanger attached to the wire at a point protected by the casing, and a line-conductor supported by the hanger.

4. The combination, with a span-wire of an electric railway, of the supplemental insulated wire attached at its ends to the span-wire and forming a swinging loop below the same, the protecting-casing, as L, and the insulator-hanger attached to the loop over the casing and comprising a metal clip, and an insulator intermediate between the clip and the trolley-wire, as described.

5. The combination, in an electric railway, of the insulator, the surrounding clip around which the supporting transverse wire is passed, the ear for sustaining the line-conductor, and the fastening screw or bolt passing down through the insulator and having its head protected by insulating material, as set forth.

6. The combination of the metal clip having a central opening and the insulator having a stem projecting into said opening, with the bolt having a vertical bearing upon the

metal clip and passing down through the insulator, and the supporting-ear for the conductor, as set forth.

7. The combination of the metal clip having hooked offsets around which passes the transverse supporting-wire, the insulator having a stem passing through an opening in the clip, and a water-shed, the supporting-ear for the conductor, and the bolt passing down

through the insulator and securing the different parts of the hanger together, as described.

Signed at Lynn, Massachusetts, June 16, 1890.
